(57) **CLAIM**

The ornamental design for a tongue sponge, as shown and described.

DESCRIPTION

FIG. 1 is a front perspective view of a tongue sponge according to the invention;

FIG. 2 is a left plan side view of the tongue sponge of FIG. 1, with the right-side view being a mirror image thereof;

FIG. 3 is a front plan view thereof;

FIG. 4 is a rear plan view thereof;

FIG. 5 is a top plan view thereof;

FIG. 6 is a bottom plan view thereof; and,

FIG. 7 is an exploded view of the tongue sponge showing the head of the tongue sponge being removed.

The broken lines shown in FIGS. 1-4 and FIGS. 6-7 illustrate portions of the tongue sponge that form no part of the claimed design.
